UNITED STATES PATENT OFFICE.

MARCUS B. BEHRMAN, OF NEW YORK, N. Y., ASSIGNOR TO THE LOX SEAL CORPORATION, OF BROOKLYN, NEW YORK, A CORPORATION OF NEW YORK.

FASTENING MEANS.

Application filed April 17, 1925. Serial No. 23,833.

To all whom it may concern:

Be it known that I, MARCUS B. BEHRMAN, a citizen of the United States, and a resident of the city and State of New York, county of Kings, have invented new and useful Improvements in a Fastening Means, of which the following is a specification.

My invention relates generally to tie member securing means and involves an arrangement whereby the tie element or member secures articles of merchandise in fixed association and against separation without detection and coordinately involves an arrangement whereby terminal ends of a tie member can be secured against separation, and while so secured can be made to approach each other by increments so as to correspondingly draw together the tie member about the merchandise.

20 Furriers in particular are presented with the difficulty that in shipping a number of skins, one or more skins are frequently removed from the group and such fact cannot be detected unless and until the skins are counted and my invention has particular utility to prevent such practice occurring without detection. Its utility however extends to the field of packaging generally and it will be understood, as this application is 30 read that the fastener amendment can serve even a broader field.

I am aware of the fact that devices have been constructed for this purpose in which terminal portions of a tie member were secured to a fastening member which held the terminal portions against separation, but in those characters of devices with which I am acquainted, either there is a provision by which the tie member can be released 40 from the fastener at will or where such is not the case, or only tie member of determinate length can be employed or the terminals of the tie member must be specially treated or specially formed so as to adopt them for the fastening operation and in either case.

Furthermore I am not aware of the device of this character in which the tie member is intended to be secured about merchandise with the terminal thereof held against separation, and while so held to be moved toward each other so as to tighten the tie member about the merchandise, or in which an indeterminate length of conventional material such as wire can have one

or both of its terminal ends secured without special treatment of such terminal end or ends.

One of the objects of my invention is the provision of an arrangement whereby an indeterminate length of wire or similar material can be employed so as to have the ends of such length locked together with the wire secured to and about an article of merchandise or a group of such articles so that not only will any label or tag attached to such wire be incapable of removal without detection, but the merchandise or the groups of articles so associated cannot be separated or disassociated or otherwise similarly tampered with without that fact being at once apparent.

Another object of my invention is the provision of an arrangement wherein the shackle or tie which passes about the article of merchandise or the group of articles can be of a conventional type such as wire on a reel or spool, from which the desired length can be cut, and furthermore, an arrangement by which no predetermined length of wire is necessary in order to have the device function and no special treatment of the terminals of any length is necessary in order to have it cooperate for providing the desired engaging action.

My invention further involves the provision of an arrangement whereby a tie member and more particularly a tie member of the conventional type and of indeterminate length can be secured about merchandise with its terminal ends held against separation and while so held can be tightened about such merchandise, so as to tightly grip the merchandise and prevents the disassociation thereof without detection.

For the attainment of these objects and such other objects as may hereinafter appear or be pointed out I have illustrated embodiments of my invention in the accompanying drawings, wherein:

Fig. 1 is a cross sectional view through one embodiment of my invention;

Fig. 2 is a view partly in cross section through a second embodiment of my invention; and

Fig. 3 shows a group of skins secured together against separation by my fastening means and with a label attached thereto.

Upon viewing Fig. 1 of the drawing, it will be observed that in this embodiment

there is provided a hollow casing in which there is received the plunger 12 arranged so as to slide freely within the casing and having its forward end tapered as shown at 13. 5 This plunger has a circular passage 14 longitudinally therethrough of a diameter to freely receive a terminal end of a tie member which in the illustrated embodiment is shown as in the form of a length of a conventional type and thickness of wire. 10 This plunger 12 is provided at its forward or tapered end 13 with the transverse passages 15 extending from the central longitudinal passage 14 to the outer surface and 15 of a size sufficiently large to receive the balls 16 for movement therein transversely of the plunger 12. These balls are of a diameter with relation to the length of these transverse passages 15 so that they can at 20 the same time extend beyond the passages at both ends so as to simultaneously project part way into the longitudinal passage 14 and be in contact with the inner wall of the conical passage 11 of the casing 10. This 25 plunger 12 as shown in the drawing is materially shorter than the length of the interior of the casing 10 so that it will have movement longitudinally of and within such casing and a spiral spring 18 is positioned 30 into the casing 10 and in back of the plunger 12 with one end of the spring in abutting relation to the plug 19 fixedly associated with the casing 10 at its rear and the opposite end of the spring abutting against the 35 rear surface of the plunger 12.

A flexible tie member 24 of a conventional type such as a length of wire is fixed to the rear end of the casing as by having one of its terminal ends 23 upset against the 40 inner surface of the plug 19 and has its other terminal end 25 free. The casing 10 is further provided in its forward wall with the passage 21 through such wall which passage is in registry with the passage 14 45 through the plunger 12 and is also of a dimension so as to freely receive a terminal end of a tie member such as a wire freely and yet without any substantial space thereabout.

50 In the use of a device of this character, it will be understood that the spring 18 will normally retain the plunger 12 in its extreme forward position to the left of Fig. 1 and the action of the inclined surface 11 at 55 the forward end of the casing will be such as to force the balls 15 inwardly toward each other and into the central channel 14. Upon the insertion of the terminal end 25 of the wire 24 through the opening 21 and 60 into the passage 14, such terminal end will contact with the balls 15 and force them apart and in such action results from the coaction of the balls 15 with the inclined surface 11, until a point is reached, where 65 the space between the balls is sufficient to

70 permit the terminal end 25 to pass between the balls for the desired distance and upon a release of this invention the spring 18 will act to move the plunger forwardly to the left as far as possible which is determined by the relative dimensions of the parts. Any attempt to withdraw this terminal end will be prevented because such action will tend to draw up the balls 15 75 forwardly with it and any such tendency will cause the inclined wall 11 to still further engage and clutch the terminal end 25 against withdrawal.

I am aware of the fact that attempts have hitherto been made to automatically secure 80 the terminal end of a tie or connecting member to a fastening member to which the other end of the tie or connecting member has been permanently fixed but in all of these arrangements with which I am acquainted, none of them have provided 85 against the withdrawal whether accidentally or intentionally of the terminal end so automatically connected and clutched to the fastener, and in which as far as I am aware, 90 has the tie member been of the conventional type so that, for instance, where it is desired to secure the two terminal ends 95 against separation by the fastener about the articles of merchandise, such as skins that the length of the tie member can be indeterminate so that the starting with the maximum length which may be necessary a terminal portion thereof of any desired 100 length may be cut away and the new terminal portion thus provided cooperate with the fastener without any impairment of its 105 efficiency.

In Fig. 2 of the drawing, I show a different embodiment in my invention which 105 is particularly adapted for my purposes and in which the tie member is absolutely independent of the fastener and in which therefore, no special provision has to be made 110 for securing the tie member thereto and in this embodiment, I show a hollow casing 30, hollowed out to form a compartment 31, the opposite ends of which are narrowed or tapered as shown at 32 and 33. Within the opposite ends of this casing, are arranged 115 plunger members 42 each having a central passage 43 therethrough and the transverse passages 44 within which transverse passages are received the balls 45, the forward end of each of these plungers being tapered 120 as shown at 46. Each plunger in all respects is constructed and functions as does the plunger 14 in the embodiment of Fig. 1. The casing is provided at its opposite ends with the openings 47 and 48 therethrough 125 which preferably register with the longitudinal openings 43 through the plungers and each of which serves the same purpose as the opening 21 in the embodiment of Fig. 1. A spring 50 preferably of the spiral 130

type is received between the plungers so as to force both plungers to their extreme positions at the ends of the casing.

The type of fastener securing element of Fig. 2 possesses the advantage that it can be employed with tie members of indeterminate length and which originally may be in the form of a wire on a reel or spool from which any desired length can be removed. One terminal end of the length so removed is inserted through one of the openings 47 or 48 in the end walls of the casing 30 and into the longitudinal passage 43 in the adjacent plunger member to cause a clutching engagement between the balls 45 and such terminal end against removal so that the withdrawal to such terminal end from the casing is therefore impossible without destruction of either the tie member or the fastener. The tie member is then passed about the merchandise such as the group of skins A in Fig. 3 so as to tightly grip them and the opposite terminal ends inserted through the opposite openings in the opposite end of the casing and into the passage 43 in the other plunger to secure the gripping engagement therebetween.

One of the important features of my invention is the fact that the fastening element which is to secure the terminal ends of a tie member against separation is of such a character with reference to the tie member that the terminal portions of the tie member can be inserted therein for association against separation and by stepped increments the tie member about the merchandise shortened so that therefore assuming one terminal end of the tie member locked in position to the fastener against withdrawal or removal and the tie member passed about the merchandise, the gripping engagement between the tie member and the merchandise, can be increased by increments corresponding with the increments by which other terminal ends of the tie member are inserted and pushed into the locking member.

It is the practice among furriers to associate together by a string a number of skins which are shipped to the dyeing establishment which skins are tied as a group while dyed together. In this connection, the employment of a wire is particularly useful because of the fact that the wire is not affected by the dye; furthermore, the casing 10 may have thereon the name of the furrier from whom the skins are received so that the liability of the tag being removed or lost or destroyed during the shipping and dyeing process is eliminated. In this manner, I

attain the advantages not only inherent in wire, but also the special advantages of such material in connection with the manner in which the merchandise secured thereby is to be operated upon.

Of course, it will be understood that while I have disclosed my tie member as secured about the skins and holding them by friction, it could be effected by having a wire passed through the skins.

Having thus described my invention and illustrated its use, what I claim as new and desire to secure by Letters Patent is:

1. A fastener comprising, in combination, a wire substantially symmetrical and uniform throughout its length, a casing having an opening in one end properly proportioned to receive an end of the wire inserted slidably therein, means at the opposite end of the casing to maintain an end of the wire associated therewith, a spring-pressed block within the casing having a passage in alignment with the opening in the casing, and a member carried by the block proportioned for wedging engagement with the wire and actuated by the spring action.

2. A fastener comprising, in combination, a wire substantially symmetrical and uniform throughout its length, a casing having a tapered end and an opening in said tapered end properly proportioned to receive an end of the wire inserted slidably therein, means at the opposite end of the casing to maintain an end of the wire associated therewith, a spring-pressed tapered block within the tapered end of the casing having a passage in alignment with the opening in the casing, and a member carried by the block proportioned for wedging engagement with the wire and actuated by the interaction of the spring and the taper of the casing.

3. A fastener comprising, in combination, a wire substantially symmetrical and uniform throughout its length, a casing tapered at one end and having an opening in the tapered end properly proportioned to receive an end of the wire inserted slidably therein, means at the opposite end of the casing to maintain an end of the wire associated therewith, a spring-pressed tapered block within the casing having a passage in alignment with the opening in the casing and a lateral opening, a member inserted into the lateral opening and carried by the block proportioned for wedging engagement with the wire and actuated by interaction of the spring and the taper of the casing.

In witness whereof, I have signed this specification, this 15th day of April 1925.

MARCUS B. BEHRMAN.
